UNITED STATES PATENT OFFICE.

MARSHALL CAINE, OF BARBERTON, OHIO.

SEGMENT-BLOCK.

1,347,247.

Specification of Letters Patent. Patented July 20, 1920.

Application filed December 3, 1918. Serial No. 265,161.

To all whom it may concern:

Be it known that I, MARSHALL CAINE, a citizen of the United States, residing at Barberton, in the county of Summit and State of Ohio, have invented new and useful Improvements in Segment-Blocks, of which the following is a specification.

My invention in segment blocks relates to hollow blocks adapted for conjoint employment in the formation of sewer pipes and similar tubular structures, whereby the same are formed in sections possessing great strength with continuous air spaces throughout the length of the pipe.

The primary object of the invention, therefore, is the provision of a block in the nature of an arch section adapted for building into pipe formation by interlocking side joints between adjacently positioned blocks throughout the circumference of the completed pipe while the ends of the blocks are suitably flanged to form end joints for the adjacent blocks in the nature of a hub upon the complete pipe, it being understood that longitudinal openings through the blocks provide continuous air spaces throughout the length of the pipe, spaced apart around the entire wall of the pipe.

With these general objects in view, the invention will be now fully described in connection with the accompanying drawing and in which like reference characters designate corresponding parts throughout the several views.

In the drawings,

Figure 1 is a perspective view of one of my form of blocks showing the flanged end thereof.

Fig. 2 is a similar perspective view showing the opposite end of the block.

Fig. 3 is a central longitudinal sectional view of two blocks assembled, and

Fig. 4 is an end elevational view showing blocks assembled in pipe forming arrangement, partly broken away.

Referring more in detail to the drawings, it will be understood that my block is formed of suitable dimensions for laying a sewer pipe or conduit of the desired diameter and broadly provides an outer wall 10 slightly arcuate in cross section with an inner wall 11 parallel thereto and of slightly less width, whereby opposite side walls 12 and 13 which connect the same together are

slightly convergent inwardly corresponding to radial lines of the completed sewer pipe.

A central longitudinal web 14 of each block divides the same into longitudinal air spaces 15 which will be continuous throughout the pipe wall when completed. The side wall 12 of each block has a longitudinal groove 16 adapted for the reception of a complementally shaped rib 17 longitudinally provided upon the wall 13 thereof so that the side walls of adjacent blocks are adapted to be dove-tailed together in a strong locking joint when assembled and at which times the walls 10 of the blocks will form the outer circular face of the pipe while the walls 11 of the blocks will form the inner circular face thereof.

The ends of my blocks are adapted for abutting engagement when in pipe formation with the passages 15 in alinement with each other forming air spaces which are continuous and are for insulating purposes. The outer wall 10 of each block is provided with an offset arcuate flange 18 at one end of the block adapted for overlying the adjacent blocks when assembled in pipe formation, thereby providing a continuous annular hub or flange circumferentially of the completed pipe which affords a strong and tight joint for the sectional structure.

The web 14 is cut away or notched at its inner side adjacent the wall 11 as at 19 while a projecting arcuate flange 20 upon the opposite end of the block is provided inwardly of and parallel with the outer flange 18. By this arrangement, the inner flange 20 of each block will project within the air spaces 15 and the notch 19 of each adjacently positioned block when the blocks are assembled in longitudinal alinement as heretofore described. In joining the blocks together at their ends, a suitable amount of mortar 21 is preferably employed upon the entire contacting ends of the blocks as well as upon the inner faces of the flanges 18 and covering the inner flanges 20. A pipe formed after the manner of my invention as best illustrated in Fig. 4 of the drawings will possess great strength being in the nature of solid pipe sections, although formed of separate blocks, it being understood that mortar may also be employed between the engaging dove-tailed sides of the connected blocks if found desirable. The inner flange or lip 20

greatly braces the structure and with the outer flange forms a strong and watertight joint.

What I claim as new is:—

- 5 1. A block of the type described having longitudinal air spaces therethrough and an intermediate radial web provided with a notch at one end of the block, the block further having outer and inner walls in parallelism and arcuate in cross section, an arcuate flange upon the outer wall of the block at the opposite end thereof adapted for forming an annular flange when a plurality of the blocks are assembled in pipe formation, and
- 10 15 an arcuate flange upon the inner wall at the flanged end of the block adapted for seating reception within said notch and air spaces when the blocks are arranged in end to end position.
- 20 2. A segment block including concentric spaced arcuate inner and outer walls connected by radial side walls and a radial web to form open longitudinal air passages in the block, said web having a notch in one end thereof adjacent said inner wall, an offset outwardly projecting arcuate flange formed upon the inner wall at the opposite end of the block and arranged for reception within the notch and the ends of the air passages of
- 25 30 an adjacently positioned similar block, said arcuate flange extending from the inner face of one radial side wall to the inner face of the other side wall, and an offset outwardly projecting arcuate hub flange formed upon the outer wall at said opposite end of the block.
- 35

3. A segment block including concentric spaced arcuate inner and outer walls connected by radial side walls and a radial web to form open longitudinal air passages in the block, said web having a notch in one end thereof adjacent said inner wall, an offset outwardly projecting arcuate flange formed upon the inner wall at the opposite end of the block and arranged for reception within the notch and the ends of the air passages of an adjacently positioned similar block, said arcuate flange extending from the inner face of one radial side wall to the inner face of the other side wall, one of said side walls having a longitudinal undercut groove, a complementally - shaped longitudinal rib on the other side wall formed for snug reception within the undercut groove of a similar block positioned beside the same, and an offset outwardly projecting arcuate hub flange formed upon the outer wall at said opposite end of the block.

4. A segment block including concentric spaced arcuate inner and outer walls connected by radial walls to form an open longitudinal air passage in the block, an offset outwardly projecting arcuate flange formed upon the inner wall at one end of the block and arranged for reception within the end of the air passage of an adjacently positioned similar block, and an offset outwardly projecting arcuate hub flange formed upon the outer wall at said one end of the block.

In testimony whereof I have hereunto set my hand.

MARSHALL CAINE.
